DESIGN FOR AN AUTOMOBILE

Thaddeus R. Goldsborough, Merchantville, N. J.

Application September 21, 1934, Serial No. 53,343

Term of patent 14 years

To all whom it may concern:

Be it known that I, Thaddeus R. Goldsborough, a citizen of the United States and a resident of Merchantville, in the county of Camden and State of New Jersey, have invented a new, original and ornamental Design for an Automobile, of which the following is a specification, reference being had to the accompanying drawing, forming a part thereof.

Figure 1 is a view in perspective showing the automobile of my new design; and

Fig. 2 is a fragmentary illustration in top plan of Fig. 1.

In both figures of the drawing, the dominant features of my design are indicated in solid black lines.

I claim:

The ornamental design for an automobile, as shown and described.

THADDEUS R. GOLDSBOROUGH.
